UNITED STATES PATENT OFFICE.

MATTHEW WIARD, OF PHILADELPHIA, PENNSYLVANIA.

DESIGN FOR A POST FOR STABLE-STALLS.

SPECIFICATION forming part of Design No. 11,854, dated July 6, 1880.

Application filed February 25, 1880. Term of patent 3½ years.

To all whom it may concern:

Be it known that I, MATTHEW WIARD, of the city and county of Philadelphia, in the State of Pennsylvania, have invented an Improvement in Designs for Post for Stable-Stalls, of which the following is a specification.

My invention relates to cast-iron posts which act as a capping to a board partition, as in the case of a stable-stall, and for which it is especially designed.

It consists in constructing a cast-iron post in one piece and of a rectangular shape in general cross-section.

It further consists in having one side open, and through which opening the planking of the partition is inserted, and secured there by means of screws, and in having a portion of the sides depressed and the depression filled with ornamental work, and also in having the lower part of the post flare outward, thereby giving stability and beauty to the same.

It also consists in having a ring-piece cast upon it in place of the loose ring commonly placed upon the posts designed for stalls.

The object of my invention is to form a post which embodies in its construction strength as well as beauty, and also stability.

My object is also to connect the post so securely to the planking of the stall that it could not possibly be separated from it by the usages to which it is put, and also in preventing the injuring of the ends of the board or planking by inserting them into the post, and which at the same time gives great strength to the post, since the planking projects through one side and to the other, while the remaining two sides are resting against the wood.

The posts as usually constructed are round, and have two projecting flanges running longitudinally, and between which the planking is secured. These have the objection that they are easily broken by the horse should he kick them, and thus would leave the ends of the planking exposed. By inserting the planking into the posts I obviate this difficulty. Also, in having a ring cast solid to the post for the purpose of hitching the horse outside the stall, I do away with all the rattling noise and loose rings. The solid ring is also better, for the reason that it is easier to hitch the halter to it than the loose one.

Referring to the accompanying drawings, Figure 1 is a side elevation of my improved post. Fig. 2 is a cross-section of same, and shows the method of securing it to the stall-planking. Fig. 3 is a perspective view of a portion of the post, and shows the peculiar design of ornamental work in the sides of post.

A A and B B are the sides of the post. One of the sides, B, is open from the floor-level to nearly the top, with the exception of small braces b, and through this opening the planking C is inserted, as shown in Fig. 2.

The middle surfaces of the sides A A are depressed and rest against the planking C, to which they are secured by means of wood-screws D. By making the sides A A fit against the wood it is almost an impossibility to break it by the usage to which it is put.

The depressions on the side A A are filled in with diamond-work in raised surfaces, H, or other similar ornamentation, which give additional strength to the post. The construction of this diamond ornamental work is clearly shown in perspective in Fig. 3.

The lower part of the post—viz., from the ornamental work to the floor-level E—has the sides inclined outward, thereby giving to the same beauty and stability.

The base M at the level E has a greater area than at any section above. From the floor-level E down the post is made rough and has open sides. This is to secure it firmly in the ground.

The top of the post is ornamented, as shown in Fig. 1. All the edges F are beveled off to secure to the post a finish.

Upon the upper part of the post, and on side B, opposite to the open side, a ring or loop, K, is cast.

There is no expensive finish or drilling on a post of this design.

The portion of the post below E may be left off, and the post is then secured to the flooring by screws or nails passing through the base-plate E.

I claim—

1. In design, a post of rectangular section having two of its sides depressed and ornamented and one of the remaining sides open for the reception of planking, substantially as and for the purpose specified.

2. In design, a post of general rectangular shape in cross-section, having depressed sides which are ornamented with diamond-shaped casting and a ring or loop cast on the post at its upper end, substantially as and for the purpose specified.

3. In design, in a stable or stall post, the combination of the rectangular shape in section, beveled edges F throughout the post, diamond-shaped ornamentation H in depressed

sides A A, opened side B, inclined base M, and ring or loop K, cast solid to the post, substantially as described.

In testimony of which invention I hereunto set my hand.

MATTHEW WIARD.
